(57) **CLAIM**

The ornamental design for portions of a medical implant device as shown and described.

DESCRIPTION

FIG. 1 is a top side isometric view of a medical implant device showing my new design, according to a first embodiment;

FIG. 2 is a front elevation view thereof;

FIG. 3 is a rear elevation view thereof;

FIG. 4 is an elevation view thereof from the left side;

FIG. 5 is an elevation view thereof from the right side;

FIG. 6 is a top plan view thereof;

FIG. 7 is a bottom plan view thereof; and

FIG. 8 is a bottom side isometric view thereof.

FIG. 9 is a top side isometric view of a medical implant device showing my new design, according to a second embodiment;

FIG. 10 is a front elevation view thereof;

FIG. 11 is a rear elevation view thereof;

FIG. 12 is an elevation view thereof from the left side;

FIG. 13 is an elevation view thereof from the right side;

FIG. 14 is a top plan view thereof;

FIG. 15 is a bottom plan view thereof; and,

FIG. 16 is a bottom side isometric view thereof.

The broken lines illustrate portions of the medical implant device that form no part of the claimed design. The separations depicted by the break lines in the figures indicate an indeterminate length. Any portion of the article between the break lines form no part of the claimed design.
